SHUTTLE

James E. Segee, Lawrence, and Wilfrid J. Gosselin, Methuen, Mass., assignors to U. S. Bobbin & Shuttle Co., Providence, R. I., a corporation of Rhode Island

Application February 7, 1948, Serial No. 6,894

4 Claims. (Cl. 139—198)

1

This invention relates to what are known in the textile industry as carpet or open top, hand threading shuttles as distinguished from automatic threading shuttles by the fact that the yarn package used in such shuttles unwinds from the inside instead of from the outside of a cop or bobbin and is held in place in a recess or cop cavity in the shuttle which has side walls the inside faces of which are usually serrated, and a bottom but an open top.

There is usually an outlet eye or thread eye at what we will call the front end of such a shuttle which passes through a side wall into the recess.

In the past, it has been considered necessary to have a cover which may or may not be more or less resilient, pivoted at the back end of the recess or the end away from the front or the shuttle eye end, and of such a character that its free end is bent to form a hook to engage a latch device member which is movable and may be of various characters such as shown in the patents to: Shand, No. 339,941 of April 13, 1886; Sergeson, No. 1,278,034 of September 3, 1918; Richardson, No. 1,510,861 of October 7, 1924; Sergeson, No. 1,728,083 of September 10, 1929; and Sergeson, No. 2,071,238 of February 16, 1937.

We have discovered that by using a flat resilient cover of substantially the same width throughout its length and with a free end, which is preferably rounded, to go under a holding pin extending across the recess at the front end and having at the back end of the recess a pivot part of substantially cylindrical form in which is a tightly fitting resilient lining through which a pivot pin is driven, such a device will hold the yarn mass resiliently in place and can also be easily released from or engaged with the holding pin at the front end. The combination of the resiliency of the yarn mass, the cover itself and the elastic lining, will allow the shuttle to operate in the loom without noise and without vibration, the whole construction being much simpler than any now in use.

Our resilient construction of the cover which rests upon the substantially resilient yarn package combined with our resilient lining, all cooperate to take up the shock which a shuttle is constantly receiving from the picker action. All together they absorb this shock so as to prevent or greatly reduce the tendency, which is found in shuttles of a similar type and for a similar purpose, for the metal of the cover in certain places and of the other parts, such as the pivot or pivots, to crystallize and suddenly break. Such

2

breaks not only do damage to or destroy the usefulness of the shuttle itself but also cause enormous damage to the warp when and if the broken parts of the cover project.

5 The elimination of numerous pivot parts, arms and so forth, greatly simplifies the construction, reduces the crystallizing points and serves the desired purposes in a much better manner.

In the drawings, Fig. 1 is a top plan view of a 10 shuttle with a yarn or thread package resiliently held in place by our device.

Fig. 2 is an elevational view as from the eye side or bottom side of Fig. 1 with parts broken away and with the cover member shown in dotted lines as bent to release or lock its free end but without a thread package.

15 Fig. 3 is a broken side elevational view of a shuttle as from the pivot end of the cover with a package held in running position.

20 Fig. 4 is a lateral vertical sectional view as on the line 4—4 of Fig. 3.

The metal pivot pin H is driven through a closely fitting hole in the wood and in the lining F so that the cover moves very slowly in pressing down on the yarn package as it tends to collapse as the yarn runs out from the inside. This 25 also eliminates rattling.

The drawings represent a shuttle having a hollow body B in which is a recess R to receive a 30 yarn package P made up of thread T, the package being positioned in the recess R which has a bottom 3 and side walls 4 and 5, the inside faces of which are serrated. There is a thread eye E through which the thread T from a yarn package P passes, this eye being near the front of and passing through one side wall. The top of the recess R, shown as 6, is open.

35 For convenience, we will call the end of the recess and the shuttle where the eye is located, the front and the other end, the back.

40 A represents a holding pin which extends transversely across the front of the recess R near its top and preferably is positioned nearer the front of the recess than the eye E.

45 C represents a cover which is formed of a resilient material and comprises a shank 10 which as shown, is of uniform width and thickness and has at its front end 11 a free tip 12 which, as shown, is curved and is intended to go under the holding pin A.

50 At its other or back end 13 cover C is curved around to form a substantially tubular integral pivot member 14 and inside of this, we position a resilient lining F of cylindrical form, preferably made of a resilient material such as rub-

ber, neoprene or even fibre, with a pivot hole 15 through it, whereby pivot pin H can pass through the two walls 4 and 5 of the recess and through this hole 15 of lining F, thus providing a resilient pivot for a cover C near the back and top.

As shown, the bobbin recess R is extended at the front to form a holding pin part 20 with straight side walls 21, 21 and with flat bottom 123. The front holding pin A, as shown, is driven through one side wall 4 across this part of the recess and into the other side wall 5 above and over flat bottom 123.

At the back bobbin recess R is extended to form a pivot pin part 23 with side walls 27, 27, which are preferably a distance apart slightly greater than the width of the cover C as are also the side walls 21 and 21 of the holding pin part 20. These walls keep cover C loose but laterally in place.

Extending through the side wall 4 is a two part pivot pin hole 24, 25, which at 24 goes into pivot pin part 23 and thence as a dead end part 25 in the side wall 5. There is also preferably a pivot pin drive hole 26 extending therefrom out through the side wall 5.

In assembling the parts, the resilient lining F is forced into the substantially cylindrical pivot member 14 at the end of cover C and both are placed in position with lining hole 15 in the lining with the pivot pin hole 24, 25, whereupon the pivot pin H is driven through the part 24 of the pin hole in the wood, and through hole 15 in the lining F and into the part 25 of the pin hole so that it fits all of them with a drive friction fit.

The resiliency of lining F as well as the tight fitting into the wood of the shuttle keeps the pin from coming out of hole part 24 without the use of any screw threads, nuts or anything of that kind. When it is necessary to replace a cover or a pin or any other part or when the lining F loses its resiliency or wears down, a suitable small drive pin is pushed into drive pin hole 26 and hammered until the pivot pin H is driven out. The pin H, lining F or cover C or any or all of them can then be replaced by another or by other parts.

To install a yarn package P, cover C is bent as shown in the dotted lines Fig. 2, and its front end 11 and free end 12 are removed from between holding pin A and the bottom 123 of recess part 20 so that the whole cover can be swung out of the way. A new package can now be put in position and the cover can be swung down, bowed and its end 11 pushed in under pin A and over and on to bottom 123.

As shown in Figs. 2 and 3, the cover C when bent over a yarn package P and under holding pin A causes its end 12 to be held between holding pin A and the bottom 123 of recess 20 and its resiliency and the resiliency of the solid resilient lining F keep all metal parts in place and prevent any rattling or vibrating which would tend to crystallize any of the metal parts.

We claim:

1. A shuttle comprising a hollow body with a recess to receive a yarn package, such recess having an open top, a bottom and side walls with serrated inside faces, an extended front part, a transverse cover holding pin hole and an extended back part, a transverse pivot pin hole with a dead end, and a thread eye passing through one side wall near the front; a transverse cover holding pin which extends across the extended front part of the recess through the

holding pin hole near the top of the shuttle and nearer the front than the thread eye; a cover to partially close the open top of the recess and to hold the yarn package of the inside unwinding type in place, said cover being made of resilient material having at its front end a free tip to go under the transverse cover holding pin and at its other end being formed with a substantially tubular integral pivot member inside of which is a closely fitting resilient lining through which is a transverse pivot pin hole, the cover being pivoted in the extended back part of the recess on a transverse pivot pin; such transverse pivot pin which fits the pivot pin hole in the shuttle body with a drive fit and which goes through the extended back part of the recess and through the pivot pin hole in the lining with a drive fit.

2. A shuttle comprising a hollow body with a recess to receive a yarn package, such recess having an open top, a bottom and side walls with serrated inside faces, an extended front part, a transverse cover holding pin hole and an extended back part, a transverse pivot pin hole with a dead end passing through the extended back part, and a pin drive hole extending from the dead end of the pivot pin hole out the other side of the shuttle; and a thread eye passing through one side wall near the front; a transverse cover holding pin which extends across the extended front part of the recess through the holding pin hole near the top of the shuttle and nearer the front than the thread eye; a resilient cover to partially close the open top of the recess and to hold the yarn package of the inside unwinding type in place, said cover being made of resilient metal having at its front end a free tip to go under the transverse cover holding pin and at its other end being formed with a substantially tubular integral pivot member inside of which is a closely fitting resilient lining through which is a transverse pivot pin hole, the cover being pivoted in the extended back part of the recess on a transverse pivot pin; such transverse pivot pin which fits the pivot pin hole in the shuttle body with a drive fit and which goes through the extended back part of the recess and through the pivot pin hole in the lining with a drive fit.

3. A shuttle comprising a hollow body with a package recess to receive a yarn package, such recess having an open top, a bottom and side walls with serrated inside faces, an extended front part, a transverse cover holding pin hole and an extended back part, a transverse pivot pin hole with a dead end passing through the extended back part, and a pin drive hole extending from the dead end of the pivot pin hole out the other side of the shuttle, and a thread eye passing through one side wall near the front; a transverse cover holding pin which extends across the extended front part of the recess through the holding pin hole near the top of the shuttle and nearer the front than the thread eye; a resilient cover to partially close the open top of the recess and to hold the yarn package of the inside unwinding type in place, said cover being made of resilient metal having at its front end a free end to go under the transverse cover holding pin and resiliently engaging it and the bottom of the extended front part and at its other end being formed with a substantially tubular integral pivot member inside of which is a solid closely fitting re-

silent lining through which is a transverse pivot pin hole, the cover being pivoted in the extended back part of the recess on a transverse pivot pin; such transverse pivot pin which fits the pivot pin hole in the shuttle body with a drive fit and which goes through the extended back part of the recess and through the pivot pin hole in the lining with a drive fit.

4. A shuttle comprising a hollow body with a package recess to receive a yarn package, such recess having an open top, a bottom and side walls with serrated inside faces, an extended front part, a transverse cover holding pin hole and an extended back part, a transverse pivot pin hole with a dead end passing through the extended back part, and a pin drive hole extending from the dead end of the pivot pin hole out the other side of the shuttle and a thread eye passing through one side wall near the front; a transverse cover holding pin which extends across the extended front part of the recess through the holding pin hole near the top of the shuttle and nearer the front than the thread eye; a resilient cover to partially close the open top of the recess and to hold the yarn package of the inside unwinding type in place, said cover being made of resilient metal having at its front end a free end to go under the

5 transverse cover holding pin and resiliently engaging it and the bottom of the extended front part and at its other end being formed with a substantially tubular integral pivot member; a solid resilient lining closely fitting the pivot member and having a transverse pivot pin hole; and a transverse pivot pin which fits the pivot pin hole in the shuttle body with a drive fit and goes through the pivot pin hole in the lining of the pivot member with a drive fit.
